CLAIM

The ornamental design for a cutting insert, as shown and described.

DESCRIPTION

FIG. 1 is a perspective view of a cutting insert showing our design;

FIG. 2 is a front view of the cutting insert;

FIG. 3 is a rear view of the cutting insert;

FIG. 4 is a left side view of the cutting insert;

FIG. 5 is a right side view of the cutting insert;

FIG. 6 is a top view of the cutting insert; and,

FIG. 7 is a bottom view of the cutting insert.

The dash-dash lines in the figures represent portions of the cutting insert that form no part of the claimed design.
